DESIGN FOR A COMBINED SACHET BALL, PERFUME BOTTLE, AND HOLDERS THERE- FOR

Jean E. Vivaudou and Henry G. Lubin,
New York, N. Y.

Application August 29, 1940, Serial No. 94,721

Term of patent 7 years

To all whom it may concern:

Be it known that we, Jean E. Vivaudou and Henry G. Lubin, subject of Great Britain and citizen of the United States, respectively, and both residents of New York city, in the county of New York and State of New York, have invented a new, original, and ornamental Design for a Combined Sachet Ball, Perfume Bottle, and Holders Therefor, of which the following is a specification, reference being had to the accompanying drawing, forming a part thereof.

Fig. 1 is a side elevational view of a combined sachet ball, perfume bottle and holders therefor, showing our new design.

Fig. 2 is a front elevational view of the same.

Fig. 3 is a view of the other side from that shown in Fig. 1.

Fig. 4 is a top plan view of the same.

We claim:

The ornamental design for a combined sachet ball, perfume bottle, and holders therefor, as shown.

JEAN E. VIVAUDOU.
HENRY G. LUBIN.
